UNITED STATES PATENT OFFICE.

GEORGE W. O'DOIE, OF HAVANA, ILLINOIS.

SPIRAL-GLIDE AMUSEMENT DEVICE.

1,347,968.

Specification of Letters Patent. Patented July 27, 1920.

Application filed November 17, 1919. Serial No. 338,545.

To all whom it may concern:

Be it known that I, GEORGE W. O'DOIE, a citizen of the United States, residing at Havana, in the county of Mason and State 5 of Illinois, have invented certain new and useful Improvements in Spiral-Glide Amusement Devices; and I do hereby declare the following to be a full, clear, and exact description of the invention, such as 10 will enable others skilled in the art to which it appertains to make and use the same.

This invention relates to amusement devices, and aims to provide such a device having a spiral track down which the cars 15 glide by gravitation, to the amusement of the occupants and onlookers.

The invention has for its object the provision of a "spiral glide" amusement device of portable construction, so that the structure 20 can be knocked down or collapsed for shipment from one place to another, and the arrangement being such that when the device is set up, it will be substantial and rigid in construction to withstand the 25 strains to which it is subjected.

A still further object is the provision of spiral ascending and descending tracks, one surrounding the other, and a central mast or pole to which said tracks are connected, 30 to provide a rigid and substantial construction, and a further object is to construct said tracks and mast in sections, whereby they can be disassembled and reassembled conveniently.

35 With the foregoing and other objects in view, which will be apparent as the description proceeds, the invention resides in the construction and arrangement of parts hereinafter described and claimed it being understood that changes can be made within 40 the scope of what is claimed without departing from the spirit of the invention.

The invention is illustrated in the accompanying drawings, wherein:—

45 Figure 1 is a side elevation of the device.

Fig. 2 is a plan view thereof, portions being omitted for sake of clearness.

Fig. 3 is an enlarged sectional detail of the mast and descending spiral track.

50 In its main features, the device comprises a central mast or pole 1, a spiral descending track 2 surrounding said mast, and a spiral ascending track 3 surrounding the track 2. Said tracks are of conical form, 55 one within the other, with the convolutions extending in opposite directions, and the

tracks can be of channel-shape or other suitable form to guide the cars. The tracks are of larger diameter or increase in diameter at their lower ends, so that they will 60 brace one another, and make the structure more rigid, and the outer ascending track 3 is of larger pitch or inclination than the inner descending track 2, so that the cars can reach the top as quickly as possible, 65 and will travel through a much larger distance in descending. The tracks can be of any suitable lengths and convolutions.

The mast 1 and tracks are of sectional construction, so that they can be collapsed 70 or knocked down. The mast 1 is composed of sections 4 having their adjacent ends telescoped together, as at 5, or otherwise detachably fitted together, one on the other, and it is preferable to connect guy wires 6 75 to the upper end of the mast for holding it upright on the ground, floor or base.

Each of the spiral tracks is composed of a suitable number of sections 7, the adjacent ends of which are detachably joined, 80 as at 8, permitting the tracks to be taken apart for compact storage and shipment. The sections of the tracks and mast correspond with one another and decrease in length from the base upward. The tracks 85 2 and 3 are connected rigidly with mast 1 by means of braces 9 which have eyes 10 pivotally engaging in apertures or flanges 11 with which the mast sections 4 are provided. Said braces 9 are detachably connected, as at 12, with the tracks, and the braces extend in various directions from the mast to the tracks so as to brace the tracks and prevent them from yielding under the weight and strain of the cars. These braces 95 9, when disconnected from the tracks, can be swung against the sections of the mast when shipping the parts. If needed, props or stays 13 can be extended from the ground or floor to the tracks so as to assist in bracing them, but these may not be necessary unless the structure is built especially large or is unsafe without them.

The upper end of the ascending track 3 connects with the upper end of the descending track, so that a car after being moved off of the track 3 will gravitate down the track 2 with a spiral movement increasing in the radius of movement as the car descends. The lower convolutions of the 110 tracks 2 and 3 rest on the floor or base, and are connected by a loop 14 into which the

cars move from the track 2, and from which the cars are moved up the track 3. This loop 14 of the track extends past the platform or landing 15, from which the passengers enter the cars, and on which they alight after descending. A suitable brake 16 can be used on the track for retarding the cars when they reach the platform or landing, as well known in devices of this kind.

10 It is also preferable to use a "switch-off" track 17 shunting the loop 14, with a switch 18 for directing cars 22 into the track 17 when they are not needed. Empty cars can thus be shunted into the track 17, and from

15 there can be returned to pass up the track 3.

An endless chain or cable 20 extends along the track or loop 14 from the platform or landing 15 and up the ascending track 3, for carrying the cars up the track 3 to the top, 20 where the cars are let go so as to descend by gravity down the track 2. This chain or cable can be operated by an engine 21 or other prime mover.

By constructing the tracks and using them 25 with the mast as shown and described, the structure can be built in knock-down or collapsible type, so that it can be taken down and moved from one place to another, to be used at fairs, circuses, and the like.

30 The device can also be constructed on a small scale for use as a toy or amusement device for children, eliminating such finer details as are required on a large amusement device for carrying passengers.

35 Having thus described the invention, what is claimed as new is:—

1. An amusement device comprising a

central mast, spiral ascending and descending tracks surrounding one another and the mast, and spaced from said mast, and braces 40 connecting the mast and tracks to support the tracks from the mast, said braces being detachable for separating the mast and tracks.

2. An amusement device comprising a 45 mast, spiral ascending and descending tracks surrounding one another and the mast, braces connecting said tracks to the mast and supporting the tracks therefrom, a looped track connecting the lower ends of 50 the spiral tracks and extending to one side, loading and unloading means for said looped track, and means for moving cars or the like from the looped track along the ascending track.

55 3. An amusement device comprising a mast, spiral ascending and descending tracks surrounding one another and the mast, said mast and tracks being composed of sections, and braces detachably connecting the corresponding sections of the mast and tracks.

4. An amusement device comprising a sectional mast, sectional spiral ascending and descending tracks located one within the other and surrounding said mast, and braces 60 pivotally connected to the mast sections and detachably connected to said tracks.

In testimony whereof I have signed my name to this specification in the presence of two subscribing witnesses.

GEORGE W. O'DOIE.
